United States Patent Office

Des. 229,714
Patented Dec. 25, 1973

229,714

BODY FOR MULTI-PURPOSE RECREATIONAL VEHICLE LIGHT

George A. Knapp, Dewitt, Edward J. Nitsch, Camillus,
Fred F. Stube, Syracuse, and Ernest R. Steltzer,
Lysander, N.Y., assignors to R. E. Dietz Company,
Syracuse, N.Y.

Filed Mar. 10, 1972, Ser. No. 333,854

Term of patent 14 years

Int. Cl. D26—06

U.S. Cl. D48—32 C

FIG. 1

FIG. 2

FIG. 3

FIG. 4

FIG. 1 is a plan view of a body for multi-purpose recreational vehicle light embodying our new design;

FIG. 2 is a side elevational view thereof, the other side being a mirror image;

FIG. 3 is an end view thereof, the other end being a mirror image; and

FIG. 4 is a bottom plan view thereof.

We claim:

The ornamental design for a body for multi-purpose recreational vehicle light, as shown and described.
